UNITED STATES PATENT OFFICE

ARTHUR G. LEAKE, OF BRIDGEPORT, CONNECTICUT

TIE SCUPPER

Application filed January 9, 1930. Serial No. 419,562.

This invention relates to a scupper for protecting bridge stringers or girders, and a method and means of applying the same.

In railroad trains nowadays it is customary to dispose of waste material from the cars by allowing it to escape to the road bed through openings in the bottom of the cars. In this manner, brine from refrigerating cars as well as the discharge from lavatories and dining car kitchens is disposed of, to sink into the road bed between the ties. It has been found however, that this waste material particularly the brine from refrigerator cars has a very corrosive effect on the stringers or girders supporting the railroad tracks on bridges, and that the stringers are so rapidly corroded as to greatly weaken them to a dangerous condition and materially shorten their life and to need early replacement.

This invention has for an object to provide a method and means for protecting the bridge stringers against such corrosive action by affixing scuppers between the ties in such a manner as to prevent the corrosive waste material from reaching the stringers.

A further object of this invention is to provide a means for applying the scuppers to the ties in proper position.

With the foregoing and other objects in view, the invention consists in certain novel features of construction and arrangement of parts as will be more fully described in connection with the accompanying drawings.

In these drawings

Fig. 1 is a plan view of a section of a bridge having the scuppers in place.

Fig. 2 is an end vertical view of the bridge section in Fig. 1.

Fig. 3 is a cross section on line 3—3 of Fig. 2.

Fig. 4 is a plan view of the scupper per se.

Fig. 5 is a side elevation thereof.

Fig. 6 is an end elevation thereof, one side being shown in straightened position and the other in converging position.

Fig. 7 shows a cross section through the scupper and a tool for applying it in place.

Fig. 8 is a similar view, with a different tool for applying it in place.

Fig. 9 is a side view of the lateral projections on the pincers of the applying tool.

Fig. 10 is a cross section of a tool for scribing a slot in the ties, and

Fig. 11 shows a detail of the pincers of Fig. 8.

There is shown at 10 a stringer or girder of a bridge or the like for supporting railroad ties 11. Supported on ties 11 are the track rail 12 and guard rail 13 and also an end beam 14 as usual. It is this stringer 10 that is corroded by the action of brine or waste dripping from passing railroad trains, and it is to prevent this corrosive action that this invention is intended. A scupper 15, preferably made of about ten gauge copper bearing steel or other corrosion proof material is formed as shown on the drawings of a bottom plate 16, which may be flat or trough shaped, converging sides 17 on which are flanges 18, these flanges preferably having saw tooth edges 19. At one end of bottom plate 16 is an angularly upturned lip 21 while at the other end there is an angularly downturned lip 22. Through the sides 17 are spaced holes 23 through which nails 24 which are preferably galvanized roofing nails or of other corrosion proof material, are hammered to assist in holding the scupper 15 in place. As will be apparent from an inspection of Fig. 3, the scupper 15 is placed at an inclined angle above the stringer 10 and below track rail 12 so that it will catch any drippings from passing trains and deflect them to fall past the stringer.

The method and means for applying the scupper is shown in Figs. 7-11 inclusive. At 25 is shown a cutter having a knife edge 25' which is used for scribing a slot in the sides of the ties so that the saw teeth 19 may be placed therein. A pair of tongs 26 have handle levers 27 pivoted across each other at 28, and a pincer 29 is pivoted to each lever 27 at 30 and has a lateral projection 31 thereon to press along the length of the flanges 17. The pincers 29 are arched so as to straddle the tie 11 and a common fulcrum bar 32 is pivoted to each pincer 29 as at 33.

In applying the scupper, which may be done when building a new bridge, and likewise may be applied to old bridges already in use, inclined slots having been scribed in the proper places on the sides of the ties 5 in the proper places on the sides of the ties 11 by means of the cutter 25, the scuppers 15 are placed thereat with their saw teeth 19 projecting into or in alignment with the slots. The tongs 26 are then placed to 10 straddle a tie so that the fulcrum bar 32 rests on the tie while lateral projection 31 rests against the inside of the converging sides 17, the levers 27 being preferably at right angles to the inclined scuppers 15. 15 The handles 27 are then manually grasped and forced together and this will have the effect, due to the great leverage, of pressing the pincers 29 and their lateral projections 31 toward each other until the flanges 18 20 with saw teeth 19 are pressed into the sides of the tie, and bring the sides 17 to the position 17' in parallelism with each other against the side surface of the tie. To assist in holding the flanges 18 in place, 25 galvanized roofing nails 24 are hammered through the holes 23 in sides 17, and then a preparation of mulsified asphalt is placed over the joints between the scuppers and the ties to prevent the drippings from attacking 30 the ties and scuppers.

In Fig. 8 is shown a modified form of tongs 36 which is used between the ties instead of straddling the ties. These tongs 36 have handle levers 37 pivoted as at 38 to 35 a pair of pincers 39 which also have lateral projections 41. Instead of crossing each other, as in tongs 26, the levers 37 are bent away from each other and are pivoted to a connecting fulcrum bar 42 as at 43. On 40 the pincers 39 are projecting bosses 44 through which is passed a pivot pin 45, which projects into a V-shaped supporting clamp 46. Inasmuch as pressing the handle 45 37 together operates to separate pincers 39 and projections 41 to press flanges 18 into adjacent ties 11, a clamp 47 is placed over the pair of ties 11 to prevent the ties from tending to separate as the flanges 18 are pressed therein until the sides 17 have 50 reached the position 17'. They are nailed in place and then mulsified asphalt applied in the same manner as above.

From the foregoing description it will be apparent that there has been provided a 55 method or means for protecting the bridge girders or stringers against the corrosive action of brine or other drippings as usually fall from passing trains. It is also noted that these scuppers may be easily applied 60 to old bridges already in use to lengthen the life of the stringers already in place.

Having thus set forth the nature of my invention what I claim is:

1. A tie scupper for bridges and the like 65 comprising a U-shaped member of corro-

sion proof material, and flanges projecting laterally from the sides thereof adapted to be forced into the sides of the ties.

2. A tie scupper for bridges and the like comprising a U-shaped member, toothed flanges projecting laterally from the sides thereof, an upturned lip at one end and a depending drip lip at the other end. 70

3. In a bridge having the usual rails, ties and stringers supporting said ties, a scupper 75 for protecting said stringers against corrosive drippings, said scupper being formed of corrosion proof material and angularly attached between pairs of adjacent ties, over a stringer. 80

4. In a bridge having the usual rails, ties and stringers supporting said ties, a scupper for protecting said stringers against corrosive drippings, said scupper being formed of corrosion proof material and angularly attached between pairs of adjacent ties, over a stringer, said scupper having converging sides and laterally projecting flanges on said sides, said converging sides being adapted to be forced into parallelism with each other to thereby press said flanges into the sides of a pair of adjacent ties. 85

5. A bridge having the usual rails, ties and stringers, a scupper adapted to be placed between pairs of adjacent ties over said 90 stringers, said scupper being formed of a bottom plate, converging sides on said bottom plate and flanges on said converging sides, an angular upturned lip at one end of said flat member and a depending angular lip at the other end, said converging sides being adapted to be forcibly separated to parallelism to thereby press said flanges into said adjacent ties. 95

6. In a railroad bridge having the usual 100 stringers, ties and rails thereon, a scupper of corrosion proofed material for protecting the stringers against the corrosive action of train drippings, comprising a bottom member, side members projecting angularly upward therefrom, toothed flanges projecting laterally from said side member, said flanges being adapted to be pressed into the ties to hold the scupper in place. 110

7. In a railroad bridge having the usual 115 stringers, ties and rails thereon, a scupper of corrosion proofed material for protecting the stringers against the corrosive action of train drippings, comprising a bottom member, side members projecting angularly upward therefrom, toothed flanges projecting laterally from said side member, said flanges being adapted to be pressed into the ties to hold the scupper in place, and drip lips at either end of the bottom members. 120

8. A method of protecting bridge stringers against corrosive drippings comprising forming a scupper of corrosion proof material with converging sides and lateral flanges, scribing parallel slots in adjacent 125

sides of adjacent ties at an inclined angle to said ties, placing said scupper between said ties with the lateral flanges entering said slots, and forcibly straightening said converging sides to parallelism to thereby press said lateral flanges into said ties.

5 In testimony whereof I affix my signature.

ARTHUR G. LEAKE.
